FLEXIBLE AND CONFORMING FINGER PRINTING DEVICE

Thomas L. Norton, Fort Lauderdale, Fla.

Application October 30, 1953, Serial No. 389,220

3 Claims. (Cl. 41—4)

This invention relates to the art of finger-printing and has particular reference to a new and novel conformable platen that is particularly effective in preparing finger-prints in post-mortem work, although not necessarily restricted to such work.

The invention has for its object the provision of a platen that is flexible and compressible in a manner to substantially engage the finger to be printed for covering substantially the entire pattern area from one side of the finger-nail to the other.

A further object of the invention resides in a novel platen that is provided with finger-supporting and positioning means that is spring loaded to support the finger in the correct position for printing directly above a conformable pad over which a strip of paper is extended and with the finger-supporting means being shiftable downwardly when pressure is exerted upon the upper portion of the finger to simultaneously engage the paper and the conformable pad to provide a very effective print upon the paper over substantially the entire pattern area, and with the finger and the finger-supporting means being automatically elevated when pressure is released upon the upper surface of the finger.

It has been extremely difficult, especially in post-mortem finger-printing, to obtain a print of an adequate area of the finger, since the finger is obviously bent inwardly and relatively stiff, making it difficult to obtain a print by a rolling contact therewith. With the device of the present invention, the operator may place the finger over the finger-supporting means and with one of the finger supports being arranged substantially under the first joint of the finger, it being understood, of course, that the area to be printed has been previously manually inked after which the operator presses the finger downwardly by exerting force against the upper side, which action normally straightens the finger outwardly and a continued pressure thereon forces the inked area of the finger downwardly to contact the underlying strip of paper and the conformable pad, and by continuous downward pressure the finger will force the pad into a recess that is shaped to cause the pad and the paper to conform closely to the finger throughout that area from one side of the finger only to the other; and, upon release of the finger spring means will function to shift the finger guides and the finger upwardly to its original position, after which the paper is shifted transversely of the device and the process repeated for the other fingers.

Novel features of construction and arrangement of parts will be more clearly apparent during the course of the following description, reference being had to the accompanying drawings wherein has been illustrated a preferred embodiment of the device and wherein like characters of reference are employed to denote like parts throughout the several figures.

In the drawings:

Figure 1 is a perspective view of a device constructed in accordance with the invention,

2

Figure 2 is a transverse vertical section taken substantially on line 2—2 of Figure 1.

Figure 3 is a longitudinal vertical section taken substantially on line 3—3 of Figure 1.

5 Figure 4 is a top plan view of the device and, Figure 5 is a perspective view of a preferred form of compressible and conforming pad.

Referring specifically to the drawings, the numeral 5 illustrates a preferably integral block, formed of metal, plastic or other desirable material. The block is generally rectangular in top plan and is cut away longitudinally for its full length to form side walls 6 and shoulders 7. From the shoulders 7 the block is longitudinally and semicyclinically grooved as at 8 for its full length. The groove 8

15 as clearly shown is substantially centrally disposed with respect to the block. The block is further cut away as at 9 and 10 to form vertically disposed guide channels that extend through the shoulders 7 and the bottom of the block 11. The channel 9 slidably supports a finger plate 12 for vertical movement. The upper end of the plate 12 is formed upon an inwardly directed arc 13 for the resting support of the first joint of the finger to be finger-printed, indicated at "A." The opposite channel 10 slidably supports a combined finger-supporting plate and

20 gauge means 14 for limiting the engagement of the finger in the correct position for printing. The plate 14 at its upper end is arcuately recessed at 15 and is offset outwardly and extended upwardly at 16 to form an abutment for the proper positioning of the finger. The plates 12 and 14 are urged upwardly by a preferably flat spring 17, connected intermediate its ends upon a suitable lug 18 carried by the bottom wall 11 centrally of the block. A screw 19 serves to prevent displacement of the spring. Any desirable means may be employed to positively engage the opposite ends of the spring with the plates 12 and 14 whereby the plates may not become disengaged from their channels in the event the block is inverted. As one means of connection the ends of the spring 17 extend through slotted openings 20 of the plates 12 and 14.

25 Supported upon the shoulders 7 is a generally rectangular conformable and compressible pad 21, preferably formed of sponge rubber or the like. The pad is frictionally held upon the shoulders against displacement by the engagement of its ends in compressing relation to the side walls 6. Inwardly of each end, the pad 21 is thickened as at 22 and extends partially into the groove 8 in conforming relation thereto. The pad is further arcuately formed upwardly from its opposite sides from each of the thickened portions 22. The pad 21 has a 30 length substantially equal to the spacing between the plates 12 and 14 and in use the pad is adapted to be compressed into the groove 8 by the finger to be printed with the thickened portions 22 acting to substantially mold the pad around the finger to a point extending substantially from one side of the finger-nail to the other and, when the finger is elevated, the pad will assume its normal flat position, as shown.

35 Each of the side walls 6 at a point slightly above the pad 21 are longitudinally slotted at 23 for the passage of a strip of paper 24 upon which the finger-print impression is to be imposed. The paper 24 may be fed as needed from a roll 25 upon one side of the block 5 with the roll being supported in suitable brackets 26. From the opposite side of the device, the paper 40 may be wound upon a roll 27 supported in brackets 28 carried by the block or the paper may be pulled through the device and, as each print is made, may be severed and suitably filed. The use of the rolls for the paper 24 may be dispensed with and a single strip of paper 45 having printed indicia thereon for finger-print classification may be projected through the slots 23 and progressively moved forwardly after each print has been

made. However, the invention is not restricted to any particular arrangement of the printing paper since various automatic means may be employed for such purpose, especially when the device of the present invention is incorporated in an automatic machine or the like. It should be here noted that the spring 17 is sufficiently strong as to require a relatively heavy pressure to be exerted upon the figure in order to force the finger and the paper downwardly to compress the pad 21. The purpose of forming this spring 17 of such strength is to cause the finger of a deceased person to be straightened out when pressure is exerted thereon, and this straightening of the finger very materially aids in producing an acceptable finger-print for classification purposes and obviously, when straightening the finger by pressure thereon, it is desirable that the plates 12 and 14 be in such position as to prevent compressive engagement with the paper 24. The necessary pressure to straighten the finger is not excessive and does not require too great an additional force downwardly to produce the print.

In the use of the device, the operator first inks that area of the finger covering the desired pattern to be printed. This inking may be done by any mechanical means or when the device is employed in an automatic machine, it will be apparent that automatic means will be adapted for this purpose. After the finger has been inked, the operator places the tip of the finger upon the arcuate rest 15 with the finger abutting the stop 16. In this position the plate 12 substantially underlies the first joint of the finger. Now, by pressing downward upon the top of the finger, the finger will first straighten outwardly and a continued downward pressure forces the paper 24 into contact with the pad 21 and as the finger and paper are continuously forced downwardly, the pad 21 will be compressed into the groove 8 causing the upper surface of the pad to wrap or conform to the contour of the finger. Obviously compressing the paper over the entire area that has been inked when the finger has been compressed downwardly to the lowermost point, the pad and the paper will have conformed to the finger substantially over the entire pattern area extending from one side of the finger-nail to the other. Upon release of the finger, the spring 17 will automatically project the plates 12 and 14 upwardly to a point where the pad is completely released and the paper is free of engagement with the finger. Obviously in post-mortem finger-printing, the operator will be obliged to hold the device in various positions depending on the position of the hands of the individual to be printed.

It will thus be apparent that a very simple and highly effective platen device has been provided that greatly facilitates the production of most desirable finger-prints for identification purposes. The device is relatively small and may be conveyed to various places with little or no trouble where identification becomes necessary. The compressible pad functions to produce a full pattern print in a much more effective manner than has been heretofore accomplished by the old method of rolling the finger upon a sheet of paper with inking. The device, after the finger has been inked, is relatively automatic, requiring only that the operator place the device against the finger in the proper position and press it downwardly to a point where the pad automatically forces the paper

into conforming printing contact with the finger. The device is cheap to manufacture, is strong, durable and most effective for the purposes described. While the device has been shown as an instrument for convenient transfer from place to place, it follows that the novel construction and method of producing finger-prints in this manner may be incorporated in a machine having means to automatically shift the platen toward and from the fingers to be printed, in such case it will be apparent that the finger-printing will be from the fingers of live persons and in such a machine better prints are available and a much more rapid printing is possible.

It is to be understood that the invention is not limited to the precise construction shown but that changes in the shape, size and arrangement of parts may be resorted to as clearly fall within the spirit of the invention or the scope of the subjoined claims.

Having described my invention, what I claim as new and desire to secure by Letters Patent is:

1. A finger printing device comprising a body portion of generally rectangular form having upstanding side walls, the side walls being slotted for their major length adjacent their upper ends to form guide means for a strip of paper, the body portion being arcuately grooved downwardly throughout its length and with the groove opening upwardly, shoulders formed upon the upper surface of the body portion for its full length and with the shoulders being disposed at opposite sides of the groove, the body portion being slotted vertically and transversely adjacent each end and with the slots extending throughout the height of the body, finger supporting and positioning plates vertically shiftable in the slots of the body and with their upper ends being concave for resting engagement of the finger, one end plate having its upper end offset and extended upwardly to form an abutment to limit the longitudinal positioning of the finger, spring means carried by the body portion and engaging each of the end plates to urge them upwardly, the end plates being simultaneously shifted downwardly when pressure is exerted upon a finger supported thereon, a flexible and conforming pad having its longitudinal edges supported on the shoulders and overlying the groove for its major length, the pad partially extending into the groove, the plates serving to support the finger longitudinally of and substantially parallel to the groove and with the finger and a strip of paper being in spaced relation to the upper surface of the pad.

2. The device according to claim 1, wherein the pad is formed of sponge rubber and wherein the pad upon its under side is formed concave for its major width and with the concave extending for the full length of the pad, the pad at its points of extending partially into the groove being thickened to form comprehensive marginal portions.

3. The device according to claim 1, wherein the spring means extend through slots formed in the lower portions of the plates to prevent vertical disengagement of the plates, the pad at its opposite edges frictionally binding against the side walls.
